UNITED STATES PATENT OFFICE

165,773

COMBINED BOTTLE AND BOTTLE CAP

Paul A. Marchant, Jackson County, Mo., assignor
to Injection Molding Company, Kansas City,
Mo., a corporation of Missouri

Application April 12, 1951, Serial No. 14,805

Term of patent 14 years

(Cl. D58—26)

To all whom it may concern:

Be it known that I, Paul A. Marchant, a citizen of the United States, residing in the county of Jackson and State of Missouri, have invented a new, original, and ornamental Design for Combined Bottle and Bottle Cap, of which the following is a specification, reference being had to the accompanying drawing, forming a part hereof.

Fig. 1 is a side elevational view of a combined bottle and bottle cap, showing my new design.

Fig. 2 is a horizontal section on the line 2—2, of Fig. 1, particularly illustrating the contour of the skirt portion of the cap of the bottle.

Fig. 3 is a perspective view of the bottle with the cap removed therefrom.

The dominant feature of my design resides in the cap portion, which is shown in full lines.

I claim:

The ornamental design for a combined bottle and bottle cap, as shown and described.

PAUL A. MARCHANT.
